UNITED STATES PATENT OFFICE.

CHARLES J. MAYER, OF PHILADELPHIA, PENNSYLVANIA.

DESIGN FOR A RAIL-BOND.

SPECIFICATION forming part of Design No. 34,799, dated July 16, 1901.

Application filed November 15, 1899. Serial No. 737,134. Term of patent 14 years.

To all whom it may concern:

Be it known that I, CHARLES J. MAYER, a citizen of the United States, residing in the city of Philadelphia, in the county of Philadelphia and State of Pennsylvania, have invented and produced a new, useful, and original Design for a Rail-Bond, of which the following is a specification, reference being had to the accompanying drawings, forming part thereof.

In the drawings, Figure 1 is a view in face elevation of a rail-bond embodying my design, and Fig. 2 is a view of the same in edge elevation.

The leading feature of the design of my invention consists of the configuration and arrangement of the strands or strips connecting the end pieces or blocks of the bond.

My invention relates to the class of bonds in which end pieces are connected by flat strips or strands placed face to face and arranged in two distinct groups, springing, respectively, from opposite sides of the respective end pieces and existing in a common plane in parallelism with the planes of the flat front and rear faces of the heads of the end pieces, as distinguished from the type or class in which all the strips or strands exist in a single group.

My invention further relates to bonds of what is known as the "bolt-spanning" type as distinguished from bonds of the "in-between-bolt" type.

Referring to the drawings, *a a'* represent the respective flat heads, and *b b'* the respective bodies or plugs of the end blocks of the bond. *c c'* respectively designate the two groups of flat nested strips. The strands or strips of the group *c* merge at their respective ends into what are in Fig. 1 the upper

edges of the respective heads *a a'*, while the strands or strips of the group *c'* merge at their respective ends into the lower edges of said heads of the end pieces. The groups or strands *c c'* are each composed of two approximately straight portions and an intermediate *U*-shaped bend, the respective bends (designated *d d'*) existing in close proximity to each other in the center region of the bond, the crest of the bend of each group extending into close proximity to the innermost strand of the other group. Each group, as explained, has two approximately straight portions at the respective sides of its central bend, and the approximately straight portions of the respective groups are in parallelism with each other. The extremal portions of the outer strands or strips of the respective groups curve inward at the points where they make connection with the respective end pieces.

ff' are what I term "bolt-spaces," bounded, respectively, by the heads of the end pieces, the central bends, and the approximately straight portions of the groups of said strands, it being a characteristic of my design that the two longer opposite sides of each bolt-space are in parallelism.

Having thus described my invention, what I claim as new, and desire to secure by Letters Patent, is—

The design for a rail-bond as herein shown and described.

In witness whereof I have hereunto set my hand, this 14th day of November, A. D. 1899, in the presence of two subscribing witnesses.

CHARLES J. MAYER.
